Primary Examiner — Rashida C. Walshon(74) Attorney, Agent, or Firm — Banner & Witcoff, Ltd.(57) CLAIM

The ornamental design for a shoe, as shown and described.

DESCRIPTION

FIG. 1 is a side view of a shoe showing my new design;
 FIG. 2 is a front perspective view thereof;
 FIG. 3 is an opposite side front perspective view thereof;
 FIG. 4 is an opposite side view thereof; and,
 FIG. 5 is a top view thereof.
 The broken lines depicting the remainder of the shoe form no part of the claimed design.

1 Claim, 5 Drawing Sheets(56)
